Section 1, Public Law 690, August 8, 1946
Patent expires June 26, 1961

7 Claims. (Cl. 174—74)

1

This invention relates to an insulating casing or envelope for an electric component such as condenser or a resistance, which is closed by means of a cover of ceramic material through which pass one or more connecting leads of electrodes arranged inside the envelope, which cover is coated, at least partly, with a layer of glaze.

The use of ceramic material for obturating such envelopes at one or at both ends offers various advantages. The ingredients are cheap and the workpieces can easily be manufactured in mass-production. Those parts which are to be connected with metallic components, for example, the envelope, itself, can easily be metallized so as to allow soldering. In those cases wherein the dielectric properties have to come up to high requirements, the latter can easily be complied with by the choice of the ceramic material.

The use of ceramic material entails, however, drawbacks which arise from the nature of the surface, for this surface is rough and somewhat porous so that moisture can be easily taken up from the surroundings with the result, however, that the insulation resistance along the surface is reduced so that along this so-called surface leakage path, a leakage current may be produced. Furthermore, due to the roughened surface impurities can easily adhere to the surface, which likewise results in that the insulation resistance is reduced. In order to avoid the above-mentioned drawbacks, the surface of the workpiece consisting of ceramic material is glazed.

The present invention has for its object to give the cover for an envelope for electric components such a shape that on the one hand the surface leakage path between the parts of different potentials which are attached to the cover is lengthened in a simple manner and, on the other hand, the insulation resistance obtained with the aid of a layer of glaze is raised to the highest possible value. According to the invention this result is obtained owing to the fact that the leading-through apertures are widened at the ends so that in the cover an annular recess is formed in which a coating of glaze is provided. It should be considered that the surface leakage current may flow along two different sides so that from a member with a determined potential to another member there are two surface leakage paths of which the one extends along the top surface and the other along the bottom surface of the cover. It is therefore essential to make both paths as favorable as possible. To that end, it is desirable to coat both leakage paths,

2

at least partly, with glaze. However, if a cover which has the shape of an ordinary flat disc is placed in a glazing furnace, it is impossible directly to glaze both the top and the bottom surface of the disc, for the latter surface lies on the bottom of the furnace so that the glaze material cannot reach this surface ("dead surface").

The invention affords a construction which does not only create long surface leakage paths, but wherein also the above-mentioned drawback is obviated by the use of a layer of glaze for both leakage paths.

With the cover according to the invention, which exhibits an annular recess around the leading-through aperture, room has, so to speak, been gained so that the surface leakage path itself is lengthened whilst that portion of the leakage path which is present in the said recess can also be glazed since it does not rest on the bottom of the glazing furnace.

In one advantageous form of construction, the recess around the leading-through aperture is widened to such an extent that the disc which constitutes the cover has the shape of an inverted dish.

The invention will be explained hereinafter in detail with reference to the accompanying drawing, wherein:

30 Fig. 1 diagrammatically represents, by way of example, a first form of construction, whilst

Fig. 2 represents, as a second form of construction, a condenser which is formed as a leading-through condenser.

35 A metal cylinder 1, which is shown in section in Fig. 1, contains an electric component, for example a condenser, and is closed by a cover 2 of ceramic material which has apertures 3 and 4 through which pass leading-in conductors 5 and 6 which are fixed therein by means of cement or solder.

The layer of glaze present on the ceramic cover is indicated by a hatched area at the circumference. On the underside of the cover, there is no glaze on the surface which enters into contact with the bottom of the glazing furnace but the layer of glaze is present on the walls of annular recesses 7 and 8 which are formed owing to the fact that the lower ends of the leading-through apertures 3 and 4 are widened. As on the upper-side of the cover, the surface leakage paths between the leading-through conductors 5 and 6 and to the metal cylinder 1 consequently partly extend over glaze. It is very easy to widen the leading-through apertures in the manufacture

since this is effected simultaneously with the production of the latter, with the aid of a single former.

A condenser such as shown in Fig. 2 may be incorporated in filter systems for leading high-frequency oscillations away from a main current conductor.

For the envelope use is made of a copper tube 9 which is obturated at both ends by ceramic covers 10 and 10' which are both dish-shaped since the widening of the leading-through aperture has been continued so far that there only remains a rim 11. It appears from the figure that a disc of the shape shown is advantageous in the glazing operation since only a small surface, viz. that of the end of the rim 11, is not glazed. (Here, again, the places which are provided with a layer of glaze are indicated by hatched areas.) For securing the cover to the envelope 9, the outer circumference of the rim 11 is silver-plated so as to allow soldering as is indicated by a dash-line. The condenser C, which is present inside the envelope, is of the "wound" type which comprises in the known manner short-circuiting plates 12 and 12' in order to keep the windings, which are diagrammatically indicated by lines 13 and 13' respectively, free of induction. The condenser is wound on the central leading-through pin or tube 14 with the interposition, for the purpose of insulation, of a cylinder 15 of a material which gives rise to small high-frequency losses. By a cylinder 16 of the same insulating material, the wound condenser is separated from the envelope. The one electrode of the condenser is connected to the central pin 14 by means of a soldered joint 17. The solder 18 which connects the cover 10 with the envelope 9, also establishes the connection between the electrode 12, 12' and the envelope. The pin 14 is secured in the aperture 19 of the cover 10 by means of solder 20. In a similar manner, the other end of the pin passes through the cover 10'.

What is claimed is:

1. A casing for an electrical device subjected to high voltage in the normal operation thereof comprising a metallic casing electrically connected to one terminal of said device, a metallic tube of greater length than said casing concentrically located therein and electrically connected to the other terminal of said device, an insulating cover of ceramic material with a portion of its surface glazed and located at each end of said casing, said cover having a central aperture for the passage of said tube therethrough, said cover having an inside recessed portion with its walls glazed and an unglazed portion, a metallic coating covering a portion of said unglazed portion, each one of said insulating covers soldered at the metallic coating portion and to the end of said casing.

2. A casing for an electrical device subjected to high voltage in the normal operation thereof comprising a cylindrical metallic casing serving as one terminal of said electrical device, a metallic tube of greater length than said casing and serving as the other terminal of said electrical device located concentrically within said casing, an insulating cover of ceramic material located at each end of said casing with an aperture therein for retaining said metallic tube, said insulating cover having a recessed portion with its walls glazed and an unglazed portion, a metallic coating covering a portion of said unglazed portion, each one of said insulating covers soldered at the metallic coating portion to an end of said

cylindrical casing and to an end of said metallic tube.

3. A casing for an electrical unit of the high voltage type having at least two terminals, a central metallic tube of greater length than said unit and arranged to extend beyond each end of said unit, one of the terminals being electrically connected to said central metallic tube, an insulating tube interposed between said metallic tube and said unit, said insulating tube extending beyond the body of the said unit to insulate the other terminal therefrom, an outer metallic member for enclosing said unit, the other terminal being electrically connected to said outer metallic member, and means constituting covers of ceramic material for closing the casing located at the ends of said unit, said cover having a central aperture and an inside recess with its walls glazed and an unglazed portion, a part of the said unglazed portion being soldered to the said metallic tube.

4. A casing for an electrical device subjected to a high voltage in the normal operation comprising a cylindrical metallic casing, a circuit element within said casing and having one electrode electrically connected to the said casing, a metallic tubular member located concentrically with the said casing and having a greater length than the said casing, said tubular member being electrically connected to said circuit element and serving as the other electrode thereof, an insulating cover of ceramic material located at each end of said casing, said covers being each provided with a central aperture for retaining said tube, each of said insulating covers having an inside recessed portion with its walls glazed and an unglazed portion, a metallic coating covering a part of each of the said unglazed portions, each of said insulating covers being respectively soldered at certain of the said parts to the said casing and the said tube.

5. A casing for a high voltage circuit element mounted on a central support, comprising a metallic casing, two like ceramic covers formed with a central aperture and an annular recess surrounding the aperture, the outside cover surfaces and the surfaces of the said recess being coated with a glazed layer, the ends of the said support passing through the said central apertures and being soldered to said cover, said covers also being soldered to said casing, and means for electrically connecting the said element to the said support and to the said casing.

6. A casing for an electrical device subjected to high voltage in the normal operation thereof, comprising a metallic tubular casing, a cover portion of ceramic material having a glazed outer surface and an unglazed inner portion adapted to interfit with said tubular casing at one end thereof, and a pin member serving as a connecting lead for said electrical device, said cover portion provided with an aperture defining an inner unglazed surface portion for passing said pin through from said electrical device, the inner portion of said cover having an annular recessed portion surrounding the aperture with walls spaced apart from said pin and glazed to increase the surface insulation resistance, and the unglazed surface portion of said aperture being soldered to the ends of said pin member.

7. A casing for an electrical device subjected to high voltage in the normal operation thereof, comprising a tubular metallic casing, two ceramic covers adapted to interfit with said casing and partially enclosing said casing, a pin

member axially extending through said casing, providing connections for said electrical device, each of said covers provided with an aperture for passing said pin member through from said electrical device, said cover provided with an inner annular recessed portion surrounding said aperture, the outer and inner surface portions of said cover being coated with a glazed layer to increase the insulation resistance of said electrical device, and said pin member being secured to the wall portion of said aperture.
